Primary Examiner — Ryan Harvey(74) *Attorney, Agent, or Firm* — Andrus Intellectual Property Law, LLP**CLAIM**

The ornamental design for an exercise ball, as shown and described.

DESCRIPTION

FIG. 1 is a front perspective view of an exercise ball.

FIG. 2 is a front view thereof.

FIG. 3 is a rear view thereof.

FIGS. 4 and 5 are opposing side views thereof.

FIG. 6 is a top view thereof; and,

FIG. 7 is a bottom view thereof.

The broken line showing of portions of the exercise ball depicts environment and forms no part of the claim.

1 Claim, 4 Drawing Sheets(56)
